UNITED STATES PATENT OFFICE.

JOHN ESTOCK, OF YONKERS, NEW YORK.

MECHANICAL MOVEMENT.

1,239,169.

Specification of Letters Patent. Patented Sept. 4, 1917.

Application filed October 24, 1916. Serial No. 127,368.

To all whom it may concern:

Be it known that I, JOHN ESTOCK, a citizen of the United States, residing at Yonkers, in the county of Westchester and State 5 of New York, have invented certain new and useful Improvements in Mechanical Movements; and I do hereby declare the following to be a full, clear, and exact description of the invention, such as will enable others 10 skilled in the art to which it appertains to make and use the same.

This invention relates to new and useful improvements in mechanical movements and the principal object of the invention is to 15 provide a device for increasing power.

Another object of the invention is to provide a device consisting of a fulcrumed lever, the long end of which is driven by a suitable motor or other power generating device which lever has its short end connected to a suitable connecting rod and crank for turning a shaft to operate a drive wheel, which may be used for turning various machines.

25 A still further object of the invention is to provide a novel means for adjusting the tension on the driving chain.

A still further object of the invention is to provide a device having a balanced lever 30 so that the power wasted in moving the lever will be minimized.

With these and other objects in view the invention consists in the novel combination and arrangement of parts which will be 35 fully set forth in the following specification and accompanying drawings, in which:—

Figure 1 is a side view in elevation of a power increasing device constructed in accordance with this invention.

40 Fig. 2 is a top plan view of Fig. 1.

Fig. 3 is an end view of the device.

Fig. 4 is an end view from the opposite end of Fig. 3.

Fig. 5 is a vertical sectional view on line 45 5—5 of Fig. 3.

Fig. 6 is a horizontal sectional view on an enlarged scale taken on line 6—6 of Fig. 3.

Fig. 7 is an enlarged fragmentary detail 50 sectional view of a pair of the standards showing the method of adjusting the bearings.

Fig. 8 is an enlarged fragmentary sectional view of one end of the lever showing

the balancing weight and method of securing the same in place, and

55

Fig. 9 is a transverse sectional view on line 9—9 of Fig. 8.

Referring to the drawings, the numeral 1 designates as an entirety the base of the device comprising a pair of parallel side bars 66 2 held in spaced parallel relation by transversely extending end bars 3. Suitable intermediate bars 4 are positioned between the side bars 2 and near the end bars 3 in spaced parallel relation and extending upwardly 65 from the transverse bars 4 are standards 5 which are held in spaced parallel relation by suitable longitudinally and transversely extending bars 6 and 7 respectively. These bars 6 and 7 are arranged adjacent the upper 70 ends of the standards 5 as clearly shown in the drawings. Upon reference to Fig. 2 it will be seen that the standard to the right is supported on extensions on the bars 4 which are braced by suitable reinforcing brackets 75 8 illustrated in the drawings. Extending upwardly from the bar 3 are suitable standards 9 connected at their upper ends by a transversely extending bar 10 and a suitable connecting bar 11 extends between the 80 standards 9 and 5 as shown in Fig. 5.

Extending upwardly from the side bars 2 near the end of the machine opposite that to which the bars 4 are connected are suitable standards 12 and intermediate the ends of 85 said side bars are standards 13. These standards are arranged in pairs and connected by transversely extending bars 14 and longitudinally extending bars 15. The bars 15 are

recesses as at 16 and a suitable cap 17 is 90 fitted over each of said bars and provided with recesses 18 which align with the recesses 16 and form bearing openings in which the drive shaft of the device is mounted. Suitable braces 17' are connected 95 to the standards 12 and 13 intermediate their upper and lower ends as clearly shown in Fig. 1. Extending upwardly from the side bar 2 on the right are standards 19 supporting at their upper ends a suitable transversely extending bar 20 which is provided

100 with a central recess 21 and has a cap 22 fitting thereover which is recessed as at 23 to form a bearing in which the fulcrum pin is mounted. This fulcrum pin supports the 105

lever in operative position as clearly shown

in the drawings. Suitable standards 22' extend upwardly from the base intermediate the ends of the bars 15 and serve to brace the same centrally in order to prevent them 5 from sagging.

Mounted in the openings formed by the recesses 17 and 18 is the main drive shaft 24 carrying at its outer end the fly wheel 25 and intermediate its ends with a belt wheel 26. This belt wheel is mounted between the standards 22' as shown in Fig. 4. A crank 27 is connected to the inner end of said shaft and has rotatably connected thereto a connecting rod 28 which is pivoted at 29 to the lever designated generally by the numeral 30. The lever 30 above referred to comprises an arm 31 provided with a fulcrum pin 32 which is rotatably mounted in the recesses 21 and 23 and this arm is provided at the end nearest the fulcrum pin with a recess or pocket 33 for the reception of suitable weights 34. These weights are retained in place by a strap 35 which fits over the end of the lever as clearly shown in 25 Figs. 1 and 8. The end of the lever 31 opposite the weighted end is provided with a longitudinally extending slot 36 for the reception of the cross pin of the drive chain which will be more fully hereinafter described.

Formed in the adjacent edges of the standards 5 are recesses 37 in which suitable guides 38 of the bearing blocks 39 are slidably mounted. These bearing blocks are 35 provided with the usual caps 40 and form journals for the shafts 41 of the drive chain. Suitable wedges 42 are driven into the recesses 37 beneath the guides 38 and it will thus be seen that the distance between the 40 sprocket may be varied in order to vary the tension on the chain.

The shafts 41 are mounted between their respective pairs of standards 5 and the inner ends of said shafts are provided with 45 sprockets 42 over which the chains 43 pass. The sprockets 42 are preferably positioned near the upper ends of the standards while suitable sprockets 44 are mounted in similar bearings and on similar shafts near the lower 50 ends of the standards. The shafts of the sprockets 44 are designated by the numeral 45 and carry suitable drive sprockets 46 over which the drive chains 47 pass. These drive chains are driven by the large sprockets 48 55 mounted on the shaft 49 which is supported in suitable journal bearings 50 mounted between the standards 9 and 5.

Extending between the chains 43 and carried therewith is a suitable connecting pin 60 51 which extends through the slot 36 in the lever 30 so that upon movement of the chain the lever will be oscillated.

It will be apparent from the foregoing that in use the device is driven by connecting 65 a suitable motor or engine to the belt wheel

52 thus causing the shaft 49 to revolve and drive the sprockets 48 thus driving the sprocket 46 through the medium of the chains 47 which in turn drive the shafts 45 and the chains 43. Assuming that the connecting pin 51 is carried by the runs of the chain to the right in Fig. 5 and that the wheel 48 is operating in a clockwise direction, it will be seen that the lever 30 will move downwardly until the pin reaches its 70 lowermost distance of travel whereupon the same will start upwardly on the opposite run of the chain thus causing the lever 30 to oscillate. The oscillatory movement of the lever will cause the shaft 24 to revolve thus 75 operating the fly wheel 25 and the drive wheel 26.

While in the foregoing there has been shown and described the preferred embodiment of this invention, it is to be understood 80 that such changes may be made in the combination and arrangement of parts as will fall within the spirit and scope of the invention as claimed.

What is claimed is:—

1. A device of the class described comprising a base, a pair of standards extending upwardly from the base near one end thereof, standards extending upwardly from the base near the opposite end, a lever pivoted between the last mentioned standards, a drive wheel operated by the lever, a pair of chains between the first mentioned standards, sprockets supporting the chains, a pin extending between the chains, the lever being 95 provided with a slot to receive the pin whereby upon movement of the chains the lever will be operated and means to adjust the sprockets to control the tension of the chains.

2. In a device of the class described, a substantially rectangular supporting frame, a lever fulcrumed in the frame and extending longitudinally of the same, a driving shaft positioned adjacent to one end of the lever, a prime mover to drive said shaft, a 100 pair of spaced parallel arranged vertically extending chains positioned in rear of said driving shaft and receiving one end of said lever between the same, the end of said lever adjacent to said chains having a slot therein, a pin extending between said chains and through the slot in the lever, means connecting the drive shaft to said chains for operating the same, a driven shaft positioned adjacent the opposite end of the lever, and a crank and pitman connecting the driven shaft with the end of the lever adjacent to the same.

3. In a device of the class described, a substantially rectangular supporting frame, a lever fulcrumed in the frame and extending longitudinally of the same, a driving shaft positioned adjacent to one end of the lever, a prime mover to drive said shaft, a 110 pair of spaced parallel arranged vertically

extending chains positioned in rear of said driving shaft and receiving one end of said lever between the same, the end of said lever adjacent to said chains having a slot therein,
5 a pin extending between said chains and through the slot in the lever, means connecting the drive shaft to said chains for operating the same, a driven shaft positioned adjacent the opposite end of the lever,
10 a crank and pitman connecting the driven shaft with the end of the lever adjacent to

the same, and a counterbalancing weight detachably secured to the end of the lever opposite the slotted end thereof, as and for the purpose specified.

15

In testimony whereof I affix my signature in presence of two witnesses.

JOHN ESTOCK.
